GRASS CATCHER FOR A POWER LAWN MOWER

Michael J. Glusick, Sr., 8200 E. 1st St.,
Paramount, Calif.

Filed Nov. 19, 1962, Ser. No. 72,540

Term of patent 7 years

(Cl. D40—1)

FIG. 1

FIG. 2

FIG. 3

FIG. 4

FIG. 5

FIGURE 1 is a perspective view of a grass catcher for a power lawn mower, showing my new design;

FIGURE 2 is a front view of said grass catcher;

FIGURE 3 is a top plan view thereof;

FIGURE 4 is an elevational view showing the right side thereof; and

FIGURE 5 is a rear elevational view thereof.

The phantom showing of a power mower is depicted for illustrative purposes only.

I claim:

The ornamental design for a grass catcher for a power lawn mower, substantially as shown and described.
